UNITED STATES PATENT OFFICE.

ADOLPH E. SEINECKE, OF CINCINNATI, OHIO.

HOLDER.

Application filed July 3, 1919. Serial No. 308,430.

My invention relates to supports, holders and the like, and its object is to provide a convenient means for holding a pipe, cigar or other object on the steering-post of an automobile. A further object of the invention is, in case of a pipe, cigar or similar smoker's article held in the mouth, to enable the driver of the vehicle to lay this article aside out of the mouth without taking either hand from the steering-wheel.

My invention consists in the combination of parts and in the details of construction and arrangement of parts as will hereinafter be more fully described and claimed.

15 In the drawings:

Fig. 1 is a general perspective view of the upper parts of the steering-post and the steering-wheel showing how my invention is preferably mounted thereon;

20 Fig. 2 is a plan view of the preferred device embodying my invention;

Fig. 3 is a side elevation of the same;

Fig. 4 is a vertical cross-section on a plane corresponding to a line passing transversely 25 through Fig. 2;

Fig. 5 is a central longitudinal section;

Fig. 6 is an inverted plan view of the device;

30 Fig. 7 is an inverted plan view of the cup removed from the base and bracket; and

Fig. 8 is a plan view of the base removed from the bracket, and with the cup and bolt removed therefrom.

As my invention is exemplified herein, it 35 comprises a bracket 1 formed of a flat strip having near one end a depression 2, made by forming two compound bends 3 in the strip; past which depression the strip has the small end part 4 with an opening 5 up and down 40 through it. Some distance from the other side of the depression 2 a tongue 6 is fastened on the upper side of the bracket projecting toward the depression 2. Past this tongue 6 near the other end of the bracket 45 there are suitable openings 7 through which suitable fastening means 8 pass to fasten the device to a fixed part of the gas and spark sector, as, for instance, to one end of the segment 9, as shown in Fig. 1. In the 50 middle of the depression 2 is secured a stud 10 projecting upwardly.

The base comprises an upper disc 11 and a lower disc 12 concentric with each other, and having registered central openings. The 55 upper disc 11 has a concentric series of uni-

formly spaced radial slots 13, radially about half way out from its central opening to its periphery. There are a plurality of springs 14, each composed of a piece of spring wire bent into a loop with the junction of the 60 two members of the loop uppermost and the ends of the loop passing downwardly and radially inwardly through adjacent slots 13, then bent up around the edge of the central opening of the disc and radially outwardly 65 and downwardly onto the flat upper surface of the disc between the slots 13 and the central opening. The lower disc 12 fits tightly against the bottom of the upper disc, and the two discs 11 and 12 have in their periphery 70 a recess 15, in which the edge parts of the two discs are flanged or burred together.

The cup 16 has a central opening in its bottom, and rests on the top of the upper disc 11; the springs 14 bending outwardly 75 and upwardly around the sides of the cup 16 and, above the rim of the cup, bending in toward each other. The cup 16 has, at one side, a lateral trough-shaped projection 17 resembling a spout; and a spring 18 is 80 formed of a wire loop of different shape from the other springs 14 and has its end parts fastened in two of the slots 13 like the other springs as just described, but its members, in bending outwardly and upwardly, 85 pass to opposite sides of the projection 17 of the cup; then bend radially outwardly and downwardly into a widened loop 19 out past the end of the cup projection 17, and approximately registering with the cross- 90 section thereof.

A bolt 20 has its flat head against the upper side of the cup bottom, and passes down through the central openings of said bottom and the two discs 11 and 12, receiving on its lower end, up against the bottom of the lower disc, a nut 21, which clamps the two discs and the cup 16 tightly together so that the lower disc 12 reinforces the connections of the springs 14 to the upper disc with the cup 16 pressed tightly by said springs all around; and these two discs, these springs and this bolt and its nut become, along with the cup, a virtually unitary structure. The lower end of the bolt 20 100 has a central opening 22 which receives the stud 10 that projects up from the middle of the depression 2 of the bracket 1, while the lower side of the lower disc 12 rests against the upper surfaces of the bracket 1 at the 105 110

opposite sides of the depression 2. The lower disc 12 has a plurality of bosses 23 pressed down in it along a concentric arc where they are adapted to successively enter 5 the opening 5 in the end part of the bracket 1 as the base turns around on the stud 10. The recess 15 in the periphery of the base permits the base to pass the tongue 6 when inserted onto the bracket, and then when 10 the base is turned around on the bracket, the peripheral parts of the discs slide under the tongue 6 so that this tongue holds the base down in its rotary bearing on the stud 10. The bosses 23, entering the opening 5, 15 act as stops so that the base may be held in any one of several positions into which it is angularly adjustable.

The device is thus designed so that the bracket 1 may be permanently mounted on 20 a part of the steering mechanism and the other parts mounted thereon in such a way that they are readily removed by turning them around until the recess 15 meets the tongue 6, permitting the structure to be 25 lifted vertically off the stud 10. The remaining bracket and stud and its tongue are very small and cause no inconvenience by being permanently mounted.

A smoking pipe may be held by forcing 30 the bowl down in the main part of the cup between the plurality of springs 14, which will yieldably grasp it; the stem part of the pipe occupying the trough-shaped projection 17 and the upper and outer part 19 35 of the spring 18.

A cigar or the like occupies the trough-shaped projection 17 within the loop part 19 of the spring 18 with the lighted end inside of the main part of the cup where ashes 40 and sparks will be caught and retained by the cup.

The readily yielding springs permit the pipe, cigar or the like to be inserted therein, while held in the mouth by movement of 45 the head so that it is not necessary to use either hand in transferring the article from the mouth to the holder. This is a great convenience, and adds very much to the safety of driving the vehicle where the 50 driver desires to indulge in smoking while driving. As is well known, a smoker frequently desires to lay aside the pipe, cigar or the like; a withdrawal of either hand from the steering-wheel, especially while the 55 automobile is running fast, is a source of danger. On account of these two conflicting circumstances, careful drivers are almost precluded from smoking while driving; but with this improved holder, smoking and 60 driving may be indulged in simultaneously without hindrance to either.

The pipe, cigar or the like is readily withdrawn from the holder by grasping it with the mouth by a suitable movement of the 65 head; so that either laying aside or taking

up the article is equally convenient, and without hindrance or danger in the driving as has just been pointed out.

When smoking is not being done by the driver, the bulkier part of the device is 70 readily removed and laid away; and it is as readily applied when again needed. The angular adjustment provided for, permits the user to adjust the device very closely to the most suitable position for conveniently inserting and withdrawing the article in the manner described. It also permits this adjustment regardless of the particular position in which it may be necessary to mount the bracket 1 on the steering device of any 80 automobile. Moreover, it will be understood that the device is susceptible to modifications in its minor details, or some of these details may be omitted where the function is not required; all of these variations 85 depending upon the particular circumstance of use.

Therefore, while certain constructional details are deemed preferable in connection with my invention, and I have shown and described these rather specifically in elucidating the construction and use of my invention, as is required, I do not wish to be understood as being limited to such precise showing and description, but having thus 90 fully described my invention, what I claim as new and desire to secure by Letters Patent is:

1. A holder comprising a cup-shaped part and a trough-shaped part extending from 100 one side of said cup-shaped part, and a spring with an end fixed under said cup-shaped part and having members extending up and flanking said trough-shaped part and bending outwardly and downwardly and 105 meeting in a loop opposite the end of said trough-shaped part.

2. A holder comprising a cup-shaped part and a trough-shaped part extending from 110 one side of said cup-shaped part, a plurality of springs distributed around said cup-shaped part, with ends fixed under said part and curving upwardly around the sides of said part, and a spring with an end fixed under said cup-shaped part and having members extending up and flanking said trough-shaped part and bending outwardly and downwardly and meeting in a loop opposite the end of said trough-shaped part.

3. In combination a bracket, a cup-shaped part rotatably mounted on said bracket, and a trough-shaped part extending from one side of said cup-shaped part, said cup-shaped part having a series of engaging means disposed concentrically with said cup-shaped part and turning with the cup-shaped part, and said bracket having an opening in which said engaging means successively engage as the cup-shaped part is turned.

4. In combination a bracket, a cup-shaped 130

- part rotatably mounted on said bracket, a trough-shaped part extending from one side of said cup-shaped part, and yieldable means around said trough-shaped part, said cup-shaped part having a series of engaging means disposed concentrically with the rotation of said cup-shaped part and turning with the cup-shaped part, and said bracket having an opening in which said engaging means successively engage as the cup-shaped part is turned. 5. In combination a bracket, a cup-shaped part rotatably mounted on said bracket, a peripheral part turning with said cup-shaped part and having a recess, and means on said bracket engaging over said peripheral part to hold said cup-shaped part on said bracket but releasing said cup-shaped part when reached by said recess, said cup-shaped part having a series of engaging means disposed concentrically with the rotation of said cup-shaped part and turning with the cup-shaped part, and said bracket having an opening in which said engaging means successively engage as the cup-shaped part is turned. 6. In combination a bracket having a part for attachment to a supporting object and having a depression near one end, a stud extending up in said depression, a cup-shaped part, a base turning with said cup-shaped part having a recess in its periphery, a bearing in the center of said base, fitting on said stud, with peripheral parts of said base bearing on said bracket at opposite sides of said depression, and means on said bracket engaging over said base at one side thereof to hold said cup-shaped part on said bracket but releasing said cup-shaped part when reached by said recess. 7. In combination a bracket having a part for attachment to a supporting object and having a depression near one end, a stud extending up in said depression, a cup-shaped part, a base turning with said cup-shaped part, a bearing in the center of said base, fitting on said stud, with peripheral parts of said base bearing on said bracket at opposite sides of said depression, said base having a series of engaging means disposed concentrically to said bearing, said bracket having an opening in which said engaging means successively engage when said cup-shaped part and base are turned, and means on said bracket engaging over said base at one side thereof. 8. In combination a bracket having a part for attachment to a supporting object and having a depression near one end, a stud extending up in said depression, a cup-shaped part, a base turning with said cup-shaped part having a recess in its periphery, a bearing in the center of said base, fitting on said stud, with peripheral parts of said base bearing on said bracket at opposite sides of said depression, and means on said bracket engaging over said base at one side thereof. 9. A holder comprising a cup-shaped part having an opening in its bottom, a disk having a central opening and a concentric series of slots, a series of springs each composed of a wire bent into a loop with its end parts passing downwardly and radially inwardly through two of said slots and bent upwardly through the central opening of the disk and bent downward onto the top of said disk around said opening, said cup-shaped part resting down on said springs with the loops of the springs bending outwardly and upwardly around said cup-shaped part, and means to support said cup-shaped part and said disk and the springs carried thereby. 10. A holder comprising a cup-shaped part having an opening in its bottom, a disk having a central opening and a concentric series of slots, a series of springs each composed of a wire bent into a loop with its end parts passing downwardly and radially inwardly through two of said slots and bent upwardly through the central opening of the disk and bent downward onto the top of said disk around said opening, said cup-shaped part resting down on said springs with the loops of the springs bending outwardly and upwardly around said cup-shaped part, a lower disk lying up against the aforementioned disk against the spring parts extending from said slots to said central opening, and having a central opening registering with the central opening of the other disk, means projecting through said openings of the cup-shaped part and disks and holding said cup-shaped part and said disks together, and means to support said cup-shaped part and said disks and the springs carried thereby. 11. A holder comprising a cup-shaped part having an opening in its bottom, a disk having a central opening and a concentric series of slots, a series of springs each composed of a wire bent into a loop with its end parts passing downwardly and radially inwardly through two of said slots and bent upwardly through the central opening of the disk and bent downward onto the top of said disk around said opening, said cup-shaped part resting down on said springs with the loops of the springs bending outwardly and upwardly around said cup-shaped part, means projecting through said openings of the cup-shaped part and disks and holding said cup-shaped part and said disks together, and means to support said cup-shaped part and said disks and the springs carried thereby.

openings and holding said cup-shaped part and disk together, and means to support said cup-shaped part having a trough-shaped projection, and one of said springs having members extending up and flanking said trough-shaped part and bending outwardly and downwardly and meeting in a loop opposite the end of said trough-shaped

part, a bracket having a part for attachment to a supporting object, a pivotal bearing on 10 said bracket for said means that hold said cup and disk together, and means on said bracket engaging over a peripheral part of said disk to hold said cup and disk on said bracket.

ADOLPH E. SEINECKE.
